(57) **CLAIM**

The ornamental design for a mobile phone, as shown and described.

DESCRIPTION

FIG. 1 is a right side view of a mobile phone that has the design.

FIG. 2 is top plan view of the mobile phone.

FIG. 3 is rear view of the mobile phone.

FIG. 4 is left side view of the mobile phone.

FIG. 5 is a bottom plan view of the mobile phone; and, FIG. 6 is a front view of the mobile phone.

The outermost broken lines adjacent to the claimed areas represent the bounds of the claimed design, while all other broken lines are directed to environment and are for illustrative purposes only; the broken lines form no part of the claimed design.
